UNITED STATES PATENT OFFICE.

ERNEST T. FLEMISTER, OF DAINGERFIELD, TEXAS, ASSIGNOR OF ONE-HALF TO W. M. KNIGHT, OF DAINGERFIELD, TEXAS.

CLOTH-BOLT HOLDER.

No. 923,255.

Specification of Letters Patent.

Patented June 1, 1909.

Application filed March 22, 1909. Serial No. 484,985.

To all whom it may concern:

Be it known that I, ERNEST T. FLEMISTER, a citizen of the United States, residing at Daingerfield, in the county of Morris and 5 State of Texas, have invented a new and useful Cloth-Bolt Holder, of which the following is a specification.

This invention has relation to cloth bolt holders, and it consists in the novel construction and arrangement of its parts, as 10 hereinafter shown and described.

The object of the invention is to provide a holder of the character indicated which is adapted to be attached to a counter, or other 15 convenient support, and which is adapted to hold a bolt of cloth in such manner that the cloth may be readily paid out from the bolt or rewound upon the same, as desired.

With the above object in view the holder 20 is constructed in the form of a unitary fixture, having a basket or containing portion serving as a receptacle for the bolt, and above which is imposed a roller, over which the cloth may be passed as it is unwound from 25 the bolt.

The figure in the accompanying drawing is a perspective view of the bolt-holder, showing the same in position upon the top of a counter.

30 The holder consists of a series of parallel spaced ribs, 1, which are joined at one end with a cross rod 2. At their opposite ends the said ribs join with a cross-bar 3, and in the vicinity of the end portions of the ribs 35 which join with the said cross-bar 3, they (the said ribs) are provided with concaved curves 4. By such an arrangement it will be seen that a substantially cylindrical open-work basket is formed by the ribs and the 40 connecting bars, and that sufficient space is provided through which material contained within the basket-shaped body may be viewed. The outer end of the basket formed by the ribs as set forth is closed by a disk 5, 45 which is approximately pear-shaped in configuration. At the opposite end of the basket formed as stated is located a segment 6, which, at one end, joins with the cross-rod 2, and at its other end portion joins with the 50 cross-rod 3. That end portion of the segment 6 which joins with the cross-rod 3 projects beyond the said rod to a point approximately in a plane which passes vertically through the center of the disk 5 and the 55 center of the basket, as an entirety, and be-

tween the projecting end of the segment 6 and the lobe portion of the disk 5 is journaled a roller 7, which is spaced approximately equidistant from the cross rods 2 and 3.

The segment 6 is provided at its lower side 60 with downwardly extending lugs 8 which are adapted to be secured to the edge of the top of the counter as indicated, and the rib 4 at the opposite end of the basket is provided with downwardly extending lugs 9, which 65 are also adapted to be secured to the edge of the counter, but the edge thereof opposite to that edge to which the lugs 8 are attached. Any suitable form of securing devices may be employed for attaching the said lugs to 70 the counter. Thus it will be seen that a basket is formed which is open at one end and closed at the opposite end, and at its top portion is provided with spaces at each side of the roller 7, and between the cross rods 75 2 and 3. The basket, as so formed, is adapted to contain a bolt of cloth in a manner similar to that as indicated in dotted lines in the figure of the drawing, and when the bolt is so positioned, the end of the cloth 80 may be passed through the space at either side of the roller 7 and then over the roller and carried out along the top of the counter, where it may be examined and measured.

By reason of the fact that space is provided 85 at each of the sides of the roller 7, it is apparent that the cloth may be passed through either of the said spaces and then over the top of the roller, and may be paid out at either side of the holder, as desired.

When it is desired to rewind the cloth upon the body of the bolt it is not necessary to remove the bolt from the holder, for one behind the counter may rotate the bolt within the basket formed as stated, and such turning of 95 the bolt will rewind the cloth back over the roller and upon the body of the bolt. It will also be seen that as one end of the basket is closed, the bolt cannot be projected beyond that end of the basket, and the disk which 100 forms the closure for the end of the basket serves as a means for protecting the end of the bolt. It will also be seen that while the segment 6 is of circular configuration, it does not describe a complete circle, and therefore 105 sufficient space is afforded for the insertion of the bolt, edgewise, through the space between the ends of the segment; and the said space also affords room whereby an operator may insert his arm in the basket for the pur- 110

pose of removing the bolt therefrom, or for inserting the bolt therein.

Having described the invention, what I claim as new, and desire to secure, by Letters 5 Patent, is:—

1. A holder comprising a series of spaced ribs, a cross-rod connecting the ends of the ribs together at one side of the holder, a cross rod connecting the ends of the ribs 10 together at the opposite side of the holder, a closure located at one end of the holder, a segment member located at the opposite end of the holder and connected with the said cross-rods, and a roller journaled between 15 the said segment and the closure and spaced from the said cross-rods.
2. A holder comprising a series of curved ribs spaced from each other, a cross-rod located at one side of the holder and connecting 20 the ends of the ribs at that side of the holder together, a cross-rod located at the opposite side of the holder and connecting the ends of the ribs at that side of the holder together, a pear-shaped closure located at the 25 end of the holder and having its lobe projecting above the cross-rods, a segment-shaped member at the opposite end of the

holder and connected with the ends of the cross-rods and having a portion projecting toward the center of the holder beyond one 30 of the cross-rods, a roller journaled between the projecting end of said member and the projecting lobe of the closure and spaced from the cross-rods.

3. A holder comprising a series of curved 35 spaced ribs, a cross-rod at one side of the holder connecting the ends of the said ribs together, a cross-rod at the opposite side of the holder, connecting the opposite ends of the ribs together, said ribs having concaved 40 curves in the vicinity of the last said cross-rod, a closure at one end of the holder, an interrupted circular member at the opposite end of the holder and connected with the cross-rods, and a roller journaled between 45 one end of the said interrupted member and the said closure.

In testimony that I claim the foregoing as my own, I have hereto affixed my signature in the presence of two witnesses.

ERNEST T. FLEMISTER.
